UNITED STATES PATENT OFFICE.

ELIZABETH G. SEVIER, OF OAKLAND, CALIFORNIA.

DESIGN FOR A BOUDOIR PILLOW.

Application filed September 8, 1925. Serial No. 14,722. Term of patent 3½ years.

To all whom it may concern:

Be it known that I, ELIZABETH G. SEVIER, a citizen of the United States, residing at Oakland, in the county of Alameda and State of California, have invented a new, original, and ornamental Design for Boudoir Pillow, of which the following is a specification, reference being had to the accompanying drawing, forming part thereof.

The figure is a top view of a boudoir pillow, showing my new design.

The design consists of a rosette surround-

ed by three rows of ruffling, the ruffling being provided with a picoted edge. A cluster of "leaves" formed of two shades of material overlies the inner ruffle; the cluster, rosette and ruffling being preferably of contrasting colors.

I claim:

The ornamental design for a boudoir pillow, as shown and described.

In testimony whereof I affix my signature.

ELIZABETH G. SEVIER.
